United States Patent Office

Des. 193,873
Patented Oct. 16, 1962

193,873

EYEGLASS FRAME OR SIMILAR ARTICLE

Alexander Kono, % Kono Mfg. Co. Inc.,
69-24 49th Ave., Woodside, N.Y.

Filed Feb. 19, 1962, Ser. No. 68,893

Term of patent 14 years

(Cl. D57—1)

FIG. 1 is a perspective view of an eyeglass frame or similar article showing the new design;

FIG. 2 is a front elevational view thereof;

FIG. 3 is a perspective view of the rear looking down from the top; and

FIG. 4 is a side elevational view thereof.

The side not shown is substantially the same as the side shown.

The drawing is stippled to show contrasting areas.

I claim:

The ornamental design for an eyeglass frame or similar article, as shown and described.
